(57) **CLAIM**

The ornamental design for a golf accessory, as shown and described.

DESCRIPTION

FIG. 1 is a front, top, and left isometric view of an ornamental design for a golf accessory;

FIG. 2 is a front elevational view of the golf accessory of FIG. 1;

FIG. 3 is a rear elevational view of the golf accessory of FIG. 1;

FIG. 4 is a right side elevational view of the golf accessory of FIG. 1;

FIG. 5 is a left side elevational view of the golf accessory of FIG. 1;

FIG. 6 is a top plan view of the golf accessory of FIG. 1;

FIG. 7 is a bottom plan view of the golf accessory of FIG. 1; and,

FIG. 8 is an isometric right side view of the golf accessory of FIG. 1 shown connected to an exemplary belt clip.

The broken lines depict portions of the article and environment that form no part of the claimed design.
